UNITED STATES PATENT OFFICE.

JOSEPH B. NICHOLSON, OF STEUBENVILLE, OHIO.

APPARATUS FOR SCARIFYING PLASTIC-CLAY COLUMNS.

Application filed August 10, 1926. Serial No. 128,417.

This invention relates to apparatus for scarifying the plastic clay columns utilized in making brick, and an important object of the invention is the provision of a scarifying device which is automatically adjustable with relation to the work. Another object is to provide scarifying apparatus which is adapted to operate in such manner that the edges of the clay column will not thereby be broken. Other features of the invention will be made apparent as the description proceeds.

In general, the apparatus comprises, in association with means for conveying a column of clay or like material, scarifying devices mounted on suitable supports adjacent to the path of travel of the column and adapted to act upon the latter, each scarifying device consisting of a rotatable plate in which are adjustably mounted longitudinally extending scarifying pins.

In describing the invention in detail, reference is herein had to the accompanying drawings, in which—

25 Figure 1 is a side elevation of a scarifying apparatus embodying my invention;

Figure 2 is a transverse sectional view on line 2—2, Fig. 1.

30 Figure 3 is an enlarged top plan view of the scarifier plate or disk;

Figure 4 is an enlarged fragmentary section of the scarifier disk showing a pin mounted therein;

35 Figure 5 is a vertical sectional view of the automatically adjustable scarifier and its carriage;

Figure 6 is a transverse sectional view on line 6—6, Fig. 1; and—

40 Figure 7 is a perspective view of a brick of the character produced through the use of the invention.

Referring to the drawings, reference character 10 designates an expressing die through which the clay, in a plastic condition, is advanced in the form of a rectangular column 16. Said column is advanced horizontally and is delivered to an endless traveling conveyor which comprises rollers 20 and 21 journaled on suitable supports 18 and about which passes a belt 22 adapted for receiving thereon the clay column 16 and by which said column is advanced.

45 As the clay column is thus advanced, it is scarified, preferably on three sides thereof, by the devices which will be presently

described. Standards 15 located at opposite sides of the path of travel of the column 16 and adjacent to the die 10 carry bearings 24 on their upper ends, and rotatably 60 mounted in each of these bearings is a shaft 25 which carries on its inner end a scarifying plate or disk 26 adapted to act upon the adjacent lateral face of the column. Scarifying pins 27 are mounted on said disk 65 in a circularly arranged row of threaded openings. Each of said pins comprises a threaded bolt or screw having in the lower end thereof a socket in which is rigidly mounted the end of a slender scoring pin. 70 Fixed on the outer ends of said shaft 25 are sprocket wheels 33 connected by sprocket chains 34 to sprocket wheels 35 carried by a shaft 36 which is journaled for rotation on the upper ends of standards 75 37 and which carries a pulley or belt wheel 38 adapted to be driven by a belt 39 from any suitable source of motive power.

Another rotary scarifying device is mounted in position to scarify the upper 80 surface of the clay column 16 as the latter is advanced on the conveyor belt 22. This scarifying device comprises a circular plate or disk 40 carrying adjustable pins 41, said disk and said pins being similar in form 85 and arrangement to the disk 26 and the pins 27 shown in detail in Figs. 3 and 4. Said disk 40, which is, however, provided with a central sleeve-like extension 42 having 90 interiorly thereof a longitudinal keyway 43, is carried by a vertical shaft 44, and a splining pin or key 45 recessed in said shaft 95 is movably received in said keyway. Said shaft 44 has a bearing in and is supported by a vertical sleeve 46 which is supported 100 by a cross piece 47 which has its ends mounted upon the standards 37. The upper projecting end of the shaft 44 carries a bevel gear 49 which is operatively associated with a bevel gear 50 secured to the shaft 36. 105

An important feature of the invention is the arrangement of a scarifying device whereby the latter may automatically adjust itself to the surface of the clay column as the latter is conveyed forward, so that the 110 scorings in said surface will at all times be of substantially uniform depth. It frequently happens that the clay column will swell somewhat in parts of its length. To the end that the scorings produced by the 115 scarifying pins 41 shall be of substantially uniform depth, the scarifier disk 40 is ar-

ranged to be supported on the shaft 44 by a carriage which comprises a cross head 52 fixed on the sleeve 42, and horizontal longitudinally extending bars 51 mounted on said crosshead. The oppositely extending members of said bars have journaled in their ends rollers 57 which travel upon the upper surface of the clay column for supporting the scarifier disk 40 at a substantially fixed 10 elevation with respect to said surface. Thus, when a thicker portion of the clay column 16 passes beneath the scarifying disk 40, the latter will be elevated through the mechanism just described so that the surface of the column will be scarified to a substantially uniform depth.

As the clay column 16 advances from beneath the scarifying disk 40, some of the material removed therefrom by the scarifying pins drops to the floor while some thereof remains in more or less loosely adherent relation to the surface of the column. It is desirable to press such loose particles against the surface of the column so as to 25 more firmly unite them with the latter. For this purpose there are provided side rollers 58 and a top roller 59, the same being rotatably mounted in portions of a suitable supporting frame structure 60.

As hereinafter referred to, a feature of the invention is the arrangement of the scarifying devices so that the action thereof will not unduly break up the edge portions of the clay column as the latter is being 30 treated. To this end the pins 27 and 41 are mounted in the plates 26 and 40, respectively, so that their action does not extend to the outer edges of the clay column. As shown most clearly in Fig. 7, which illustrates a brick 16' cut from the clay column, the scoring produced by the scarifying pins does not extend to the edges of the column, there being left narrow unscarified margins or border portions 16^a, it being understood that the surface 16^b is part of the 35 upper surface of the column 16 as the lat-

ter is conveyed on the belt 22, and that the surface 16^c is a part of one of the sides of said column 16.

While I have shown the preferred construction, it will be understood that certain changes may be made in the details and arrangement of parts without departing from the present invention defined by the 50 appended claims.

What is claimed is—

1. In a scarifying apparatus, a scarifying device, a shaft for rotating said scarifying device, means for securing said scarifying device to said shaft for rotation therewith, 55 said means permitting longitudinal movement of said scarifying device on said shaft, and means whereby said scarifying device is maintained at a fixed distance from the adjacent surface of a traveling clay column 60 upon which it acts.

2. In a scarifying apparatus, a rotatable shaft, a disk fixed for rotation with and freely movable longitudinally on said shaft, a carriage in supporting relation to said disk, and scarifying pins carried by said disk.

3. In a scarifying apparatus, a rotatable shaft, a disk movable longitudinally of said shaft and rotatable therewith, pins mounted in said disk, a carriage supporting said disk and embodying rollers for riding upon a moving clay column upon which said pins act, and means for rotating said shaft.

4. In a scarifying apparatus, a rotary member, scoring pins carried by said member, means for conveying parallel to the plane of said member material to be acted upon by said pins, said pins being so arranged that the action thereof in rotation of said member is confined within an area so spaced from the edges of the surface of the material that an unscarified portion of said surface remains, and means for rotating said member.

In testimony whereof, I affix my signature.
JOSEPH B. NICHOLSON.
